UNITED STATES PATENT OFFICE.

CLARENCE W. SCHWORM, OF MASSILLON, OHIO, ASSIGNOR TO THE MASSILLON WIRE BASKET CO., OF MASSILLON, OHIO.

BUCKET-EAR.

1,339,584.

Specification of Letters Patent. Patented May 11, 1920.

Application filed March 2, 1918, Serial No. 219,984. Renewed February 16, 1920. Serial No. 359,202.

To all whom it may concern:

Be it known that I, CLARENCE W. SCHWORM, a citizen of the United States, residing at Massillon, in the county of Stark and State of Ohio, have invented a new and useful Bucket-Ear, of which the following is a specification.

The subject of this invention is a bucket ear intended primarily for use on wire buckets.

The main object of the invention is the provision of means for preventing the ear sliding on the wires.

A further object within the contemplation of the invention is the provision of means for attaching the ear to a bucket.

A still further object of the invention is the production of a simple, durable and efficient bucket ear whereby a bail or handle may be attached to a bucket.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

A practical embodiment of the invention is shown in the accompanying drawing, wherein:—

Figure 1 is a view in elevation of an ear constructed in accordance with the invention, a fragment of the bucket to which it is attached being shown;

Fig. 2 is a section on the line 2—2 of Fig. 1;

Fig. 3 is a view similar to Fig. 1 showing a modified form of attachment;

Fig. 4 is a section on the line 4—4 of Fig. 3;

Fig. 5 is a perspective view of the ear.

Referring to the drawing by numerals of reference:—

The rim of an ordinary wire bucket is illustrated at 10 and the vertically disposed side wires at 11.

The attachment forming the subject of the present invention consists of a formed plate providing an ear 12 and a base 13. The base 13 is formed with extending ends or cheeks 13' which are adapted to be bent back upon themselves to clamp about wires 11 and so bind the attachment to the bucket.

A tongue 14 is struck from the ear 12 and is bent over above the rim 10 of the bucket to prevent the attachment from sliding vertically upon the wires 11. The striking of the tongue 14 from the ear 12 provides a slot or aperture 15 for the reception of the end of a bail or handle 16.

In the modified form of attachment shown in Fig. 3 and Fig. 4, the cheeks 13' are not bent back upon themselves to embrace wires 11 but a plate 17 is placed on the opposed side of the wires and the cheeks 13' and plate 17 connected by rivets 18, or by spot welding, or in any other suitable manner.

Having thus described the invention, what is claimed as new and sought by Letters Patent, is:—

In combination with a bucket having a wire frame the upper ends of the side wires thereof terminating in a coiled edge, a bucket ear including a body, lateral cheek members forming a part of the body, a tongue cut from the ear and adapted to overlie the coiled edge of the bucket the cheek members of the body adapted to embrace the side wires of the bucket, and a plate secured to the body and coöperating therewith for securing the wires of the bucket to the body.

In testimony that I claim the foregoing as my own, I have hereto affixed my signature in the presence of two witnesses.

CLARENCE W. SCHWORM.
